JOSEPH F. LAMB, OF NEW BRITAIN, CONNECTICUT, ASSIGNEE TO LANDERS, FRARY & CLARK, OF NEW BRITAIN, CONNECTICUT, A CORPORATION OF CONNECTICUT.

ELECTRICALLY-HEATED DEVICE.

Application filed August 11, 1919, Serial No. 316,579. Renewed May 31, 1922. Serial No. 564,851.

To all whom it may concern:

Be it known that I, JOSEPH F. LAMB, a citizen of the United States, and a resident of New Britain, in the county of Hartford, State of Connecticut, have invented certain new and useful Improvements in an Electrically-Heated Device, of which the following is a specification.

This invention relates generally to electrically heated devices and has particular reference to stoves or the like of the type having a metallic supporting surface adapted to receive articles or utensils to be heated and electrical heating means associated with said supporting surface in such manner that, at least, part of the heat generated by the current passing through the heating unit is conveyed by conduction to the supporting surface from which the heat is absorbed by the article or utensil resting thereon.

The aim of the present invention is to provide an electrical heater having certain features of novelty and advantage, especially in the construction and arrangement of the members forming the supporting surface, the construction of the supporting frame therefor, and the arrangement and manner of mounting the heating element or elements.

In the accompanying drawing, I have shown my invention incorporated in a stove as it is particularly adapted therefor, but it is obvious to those skilled in this art that certain features of the invention are applicable for use in electrically heated devices of various kinds and types other than that herein illustrated and described.

In the accompanying drawing: Fig. 1 is a top plan view of a hot plate or stove in which my invention is incorporated.

Fig. 2 is a side elevation thereof, a portion of the casing being broken away.

Fig. 3 is a side view on an enlarged scale, of one of the studs and its associated insulator, and

Fig. 4 is a sectional view of one of the studs and its associated insulator.

Referring to the drawings in detail, *a* designates a shell or base having, in the present instance, the form of a pan; *b*, a frame located within the shell *a*; *c*, studs carried by the frame; *d*, electrical insulators

carried by the studs, and *e*, the resistors carried by the insulators.

The base or shell *a* which may be formed of sheet metal, has its lower portion of reduced diameter to provide a shoulder 10 on which the edge of the frame *b* is adapted to rest. The construction of the base *a* may, of course, be varied to suit requirements and, if desired, it may be constructed of heat non-conducting material, such as mineral wool, or it may be internally lined with mica or other non-conducting material.

The frame *b*, for purposes of strength and economy in manufacture, is constructed of channel iron, it being formed, in the present illustrative disclosure, of converging members 11 channel shaped in cross section and of such length that their outer ends rest upon the shoulder 10, and ring shaped channel members 12 concentrically arranged upon the converging members 11 and secured thereto in any suitable manner, as by means of rivets 13 passing through ears extending outwardly from the lower edges of the channel members or rings 12. The channel shaped members 11 and 12 are positioned with their channels opening downwardly, that is, with their flanges depending.

The studs *c* with which the insulators *d* are in contact, are secured in spaced position upon the ring-like members 12 and have, at their upper ends, enlarged heads 14, the upper surfaces of which heads are preferably all in the same plane to provide a flat surface on which the article to be heated, such as a cooking utensil, flat iron, or the like, is adapted to be placed. For the sake of convenience, the heads 14 of the studs may be referred to as forming collectively a "hot plate," this term being used in the sense that it comprises a mass of metal to be heated and from which the heat is to be absorbed by a utensil resting thereon. The lower ends of the studs are preferably of reduced diameter, and pass through openings in the horizontal webs in the ring-like members 12 and are spread or headed, as shown, to securely hold the studs in place. The shoulder 15 provided on each stud by reducing the lower end thereof, rests about the edge of the opening in the ring-like member through which the

reduced end passes so that when a utensil is placed upon the heads 14, the insulators *d* are relieved of the weight of the vessel or utensil. The heads 14, it will be noted, are of substantial size so that the tops of the heads collectively present a relatively large surface from which the heat may be absorbed by the utensil resting thereon. The members *c* are herein referred to as "studs" for purpose of convenience. It is evident that the construction of these studs may be varied without changing the functions which they perform.

The insulators *d* are shown, for illustrative purposes, as comprising cylindrical bushings encircling the studs *c* below the heads 14 thereof. These electrical insulators are formed of a material which will readily conduct heat, and they are externally grooved to receive the resistors *e*. The resistors *e*, preferably comprising coiled wires, are wound under tension and in a zig-zag fashion about external surfaces of the spaced insulators so that displacement of the resistors is guarded against. The resistors may have the usual terminal posts 16 carried by the case *a*, and in number and arrangement may, of course, be varied.

It will be seen from the foregoing description that when a device constructed in accordance with the present invention is in operation, a utensil resting upon the heads 14 will be heated, in part, by the heat conducted through the bushings and studs and, in part, by radiation of the heat through the air surrounding the resistors. The arrangement and construction of my improved heater is such that the heat generated upon passing a current of electricity through the resistors will be uniformly distributed, the tendency at all times being for the heated air within the casing to set up air currents carrying the more heated air to cooler portions in the device. The enlarged heads 14 present a large surface from which the heat is absorbed by the utensil resting thereon so that when a current is passed through the resistor or resistors, a flow of heat is immediately set up through the electrical heat conducting insulators *d* and studs *c*. Furthermore, as the heat is drawn away from the surface of the heads 14, the heat which may have been radiated or conducted to the channel iron members of the frame *b* will flow from these members through the studs to the heads. As the resistors are carried by the external surfaces of the spaced insulators, part of the heat evolved at the points of contact between the resistors and the insulators is radiated so that the bushings are not heated to an excessive degree resulting in damage to the resistors or the bushings and requiring a waste of electrical energy.

The entire device is very simple in construction and the parts may be quickly as-

sembled so that the device may be manufactured at a relatively low cost. The supporting frame *b* is light in weight, strong and durable and may be readily removed from and inserted in the case *a*. As only the lower edges of the depending flanges of the converging frame members 11 engage the case *a*, the amount of heat conducted to the case is at a minimum. Such heat as may be conveyed to the frame is either radiated therefrom, or conducted therefrom to the heads 14, so that this heat is utilized in heating the utensil resting upon the heads 14.

It is, of course, obvious that my invention is susceptible of various modifications and changes which are within the spirit of the invention without departing from the scope of the following claims, it being understood that the present disclosure of my invention is by way of illustration only and it is not to be taken as restrictive of my conception.

I claim as my invention:—

1. In an electrical heater, a plurality of spaced metallic members the surfaces of which lie in the same plane to provide a surface for receiving a utensil to be heated, a heat conducting electrical insulator for each of said metallic members, and a resistor supported by said insulators out of contact with said metallic members.

2. In an electrical heater, a plurality of spaced metallic members the surfaces of which lie in the same plane to provide a surface for receiving a utensil to be heated, a heat conducting electrical insulator for each of said metallic members in direct heat conducting relation thereto, and a resistor supported by said insulators out of contact with said metallic members.

3. In an electrical heater, a plurality of spaced metallic members the surfaces of which are in the same plane to provide a surface for the reception of a utensil to be heated, a heat conducting electrical insulator for each of said members in direct heat conducting relation thereto, and a resistor supported by the external surfaces of said insulators out of contact with said spaced metallic members.

4. In an electrical heater, a plurality of spaced metallic members the surfaces of which are in the same plane to provide a surface for the reception of a utensil to be heated, a heat conducting electrical insulator for each of said members and in direct heat conducting relation thereto, spacing means therefor, and a resistor comprising a coiled wire supported thereby out of contact with said metallic members, said insulators being spaced a greater distance from each other than the diameter of said heating coil to permit radiation of the heat throughout substantially the entire length of said coil.

5. In an electrical heater, a plurality of

- spaced metallic members the surfaces of which are in the same plane to provide a surface for the reception of a utensil to be heated, a heat conducting electrical insulator for each of said metallic members in direct heat conducting relation thereto, and a resistor comprising a coiled wire supported by the external surfaces of said insulators out of contact with said metallic members, said insulators being spaced a greater distance from each other than the diameter of the heating coil and said coil being wound in a zig-zag manner about said insulators.
3. In an electrical heater, a plurality of spaced metallic members, supporting means therefor, a heat conducting electrical insulator for each of said members and in direct heat conducting relation thereto, said metallic members having heads extending over the tops of said insulators with their top surfaces arranged to provide a supporting surface for a utensil to be heated, and a resistor supported by said insulators out of contact with said metallic members.
7. In an electrical heater, a support, studs arising therefrom and having heads the surfaces of which are disposed to form a surface for the reception of a utensil to be heated, a heat conducting electrical insulator engaging said studs below the heads thereof and a resistor supported by the external surfaces of said insulators.
8. In an electrical heater, a support, studs secured to and arising therefrom and having at their upper ends heads so disposed as to form a surface for the reception of a utensil to be heated, cylindrical bushings about said studs between the support and the heads thereof, and a resistor carried by said bushings.
9. In an electrical heater, a support provided with openings, studs having reduced ends extending through said openings and shoulders seated about the edges of the openings through which the reduced ends pass, a heat conducting electrical insulator positioned against each stud and in heat conducting relation thereto with the ends of the studs extending above said insulators to provide a surface for the reception of a utensil to be heated, and a resistor supported by said insulators out of contact with said studs.
10. In an electrical heater, a support having a plurality of spaced openings, studs having reduced ends extending through said openings with their shoulders seated about the edge of the openings, said studs having at their upper end heads arranged to provide a surface for receiving a utensil to be heated, bushings about said studs beneath the heads and resting on said support, and a resistor supported by said bushings.
11. In an electrical heater, a support having a plurality of spaced openings, studs having reduced ends extending through said openings with their shoulders seated about the edge of the openings, the lower ends of said studs being spread to secure the studs in place, said studs having at their upper end heads arranged to provide a surface for receiving a utensil to be heated, bushings about said studs beneath the heads and resting on said support, and a resistor supported by said bushings.
12. In an electrical heater, a frame comprising a plurality of connected channel iron members, studs carried by said members in spaced relation and the upper ends of which are arranged to form a surface for supporting a utensil to be heated, a bushing associated with each of said studs and in direct heat conducting relation therewith, and a resistor carried by said insulators.
13. In an electrical heater, a resistor frame comprising converging members and ring-like channel members secured to said converging members, insulators carried by said frame, and a resistor carried by said insulators.
14. In an electrical heater, a frame comprising converging channel members having their flanges depending and rings channel-shaped in cross section secured to and having the edges of their flanges resting upon said converging members, insulator spacing members secured to said frame, insulators carried thereby, and a resistor carried by said insulators.
15. In an electrical heater, a case having an internal shoulder, a frame having converging channel members arranged with their depending flanges resting on the shoulder of said case, studs carried by said frame, insulators carried by said studs, and a resistor carried by said insulators.

JOSEPH F. LAMB.
